FIG. 7.

This cross-sectional view illustrates a component assembly. On the left, a base structure is shown with internal features labeled 52, 55, 68, 61, and 71. A central vertical tube 7 is positioned within the base. A top cap 23 is secured to the base, featuring a central opening 24 and a side slot 23. A tube 72 is connected to the top cap 23. To the right, a vertical tube 35 is shown with a circular component 56 attached to its side. A slot 59 is present on the side of the tube 35. The label 'FIG. 28' is located in the lower right area of the drawing.

UNITED STATES PATENT OFFICE.

ALFRED L. RUTHVEN, OF ROCHESTER, NEW YORK, ASSIGNOR TO UNION SIMPLEX TRAIN CONTROL CO., INC., OF ROCHESTER, NEW YORK, A CORPORATION OF DELAWARE.

SIMPLEX TRAIN CONTROL.

Application filed September 27, 1923. Serial No. 665,200.

The present invention relates to train controlling apparatus, and aims to provide novel improvements in such apparatus to enhance the utility and efficiency thereof.

5 The primary object of the invention is the provision of a novel trip mechanism including cooperable trip members on the track and vehicle, and means controlled by the vehicle-carried trip member for obtaining different conditions of vehicle control 10 in a desirable, efficient and practical manner.

Another object is the provision of such apparatus including ramp means for obtaining caution and danger conditions in 15 the vehicle equipment, requiring restricted speed of the vehicle under such conditions, in combination with means for clearing the vehicle equipment and removing the speed 20 restriction when the track device at a control station is set accordingly.

A further object is the provision of a 25 novel and improved tripping device to be used on the track and operated by the locomotive or vehicle under the control of the wayside signal apparatus or circuits, whereby the practical and efficient operation of the trip mechanism is assured, without being interfered with by ice, sleet, dirt, water 30 or other foreign matter.

A still further object is the provision of 35 a tripping device including novel means for actuating and controlling the tripping member and for mounting same for movement to and from active position.

It is also an object of the invention to improve the apparatus generally in its construction and details, to enhance the utility and efficiency thereof.

40 With the foregoing and other objects in view, which will be apparent as the description proceeds, the invention resides in the construction and arrangement of parts, as hereinafter described and claimed, it being 45 understood that changes can be made within the scope of what is claimed, without departing from the spirit of the invention.

The invention is illustrated in the accompanying drawings, wherein—

80

Normal running circuit.

The vehicle equipment includes an electro-magnet 15 which controls an air valve or other device, so that when said magnet is deenergized the brakes are applied, the steam, electrical, or other power shut off, or both, so that such magnet must be kept energized in order that the locomotive or train may proceed. The circuit of the magnet 15 includes a direct current generator 14, or other source of electrical energy, the magnet 15, a movable contact brush or blade 16 carried by the centrifugal speed control governor 17, a conductor 18, a switch 20, a conductor 21, a switch 22, and conductor 27. The opening of either switch will open the circuit, and will serve as well as the accidental breaking or shorting of the circuit, to deenergize the magnet 15 and apply the brakes.

100

The switches 20 and 22 are carried by and insulated from the respective switches 28 and 29 under the influence of the corresponding electro-magnets 30 and 31, which, when energized, hold said switches closed.

The magnets 30 and 31 are in separate normally closed circuits controlled by the responsive trip device 23 which has an oscillatory disk 24 provided with the switch segments 32 and 33 engaged by the respective contacts 25 and 26.

The circuit of the magnet 30 includes the generator 14, conductor 27, disk 24, segment 32, contact 25, conductor 33, magnet 30, switch 28 and conductor 34, and the opening of the circuit between the segment 32 and contact 25 will deenergize the magnet 30. This will permit the switches 20 and 28 to drop open, and the switch 28 having been released cannot be reclosed unless the circuit of the magnet 30 is completed through some other channel. The switch 20 being opened will establish caution conditions, as will hereinafter more fully appear.

The circuit of the magnet 31 includes the generator 14, conductor 27, disk 24, segment 35, contact 26, conductor 36, magnet 31, switch 29 and conductor 34, whereby the opening of the circuit between the segment 35 and contact 26 will deenergize the magnet 31 and permit the switches 22 and 29 to drop open. The switch 29 having moved open will prevent the switch from being reclosed unless the circuit of the magnet 31 is completed through some other connection, thereby keeping the switch 22 open, which obtains danger vehicle conditions, as will hereinafter more fully appear.

Caution speed control circuit.

The deenergization of the caution magnet 30 and opening of the caution switch 20 will produce caution conditions in the vehicle equipment, with the switch 22 closed. Under these conditions, the circuit of the magnet 15 includes a speed control shunt paralleling the switch 20. The circuit of the magnet 15 now includes the generator 14, magnet 15, brush 16, a caution contact strip 37 arranged to be engaged by the brush 16 when the vehicle is travelling below a predetermined speed (say from fifteen to thirty miles an hour), conductor 38, conductor 21 (conductor 18 and switch 20 being shunted by the contact strip 37 and conductor 38), switch 22, and conductor 27. The strip 37 is of such a length that the brush 16 will be removed therefrom, to open such caution control circuit, when the allotted speed is exceeded, thereby deenergizing the magnet 15 to apply the brakes. Caution speed control therefore obtains when the switch 20 is open, compelling the completion of the circuit by way of the

caution control contact strip 37 of the speed control device. The governor 17 is operated from a wheel or other movable member, for rotating the governor according to the speed of the vehicle, and for raising the brush 16 in accordance with the speed. If the permissive speed of the vehicle, under such caution conditions, is exceeded, the brush 16 will be lifted off the contact strip 37 so as to open the circuit of the magnet 15 and to apply the brakes until the speed is reduced and the brush 16 is returned to the strip 37.

Danger speed control circuit.

A more reduced speed is required under danger conditions than under caution conditions, and the train must first be brought to a stop before it can proceed, after a danger indication is received by the vehicle equipment, this being brought about by the opening of the switch 22, which will enforce danger speed control until said switch 22 is again closed. The danger speed control circuit shunts the conductor 18 and switches 20 and 22, and also shunts the contact strip 37 and conductor 38 of the caution speed control circuit. Such danger speed control circuit includes the generator 14, magnet 15, brush 16, a contact 40 engaged by the brush 16 when the vehicle has come to a complete stop, conductor 41, an electromagnet 44, conductor 45, engineer's or motorman's switch 46, conductor 47, and conductor 27. Thus, when the vehicle has come to a stop, with the brush 16 engaging the contact 40, and the engineer or motorman holds the switch 46 closed, the circuit of the magnet 15 is completed, to energize the magnet 15 and release the brakes. The magnet 44 is also energized, thereby attracting the switch 43 to which the conductor 41 is connected, and moving the switch against the contact 48 to change the circuit connections and to permit the train to proceed at a slow speed under danger conditions. The danger speed control circuit, after the lifting of the switch 43, now includes the generator 14, magnet 15, brush 16, a danger speed control contact strip 49, which is shorter than the contact strip 37 to restrict the speed to say twelve miles per hour or less, conductor 50, contact 48, switch 43, magnet 44, conductor 45, switch 46 held closed, conductor 47 and conductor 27. The vehicle can then proceed below the maximum danger speed, the brush 16 sliding upwardly on the strip 49, and if such speed is exceeded, the brush 16 is removed from the strip 49, which will not only deenergize the magnet 15 and apply the brakes, but which will also deenergize the magnet 44, letting the switch 43 drop away from the contact 48. This will open the circuit through the contact strip 49, thereby keeping the brakes applied until the train is again brought to a stop to

return the brush 16 against the contact 40, in which event the switch 43 is again lifted into connection with the contact 48 so that the vehicle can proceed again under danger

5 speed control. A stop will be enforced, however, whenever the danger speed is exceeded under these conditions.

The governor 17 is preferably arranged in full view of the engineer so that he may 10 see same while operating, to be assured that the governor is in working condition when the train is moving, or other protective measures can be employed.

The danger speed control prevails whenever 15 the switch 22 is opened, compelling the completion of the circuit of the magnet 15 by way of either the contact 40 or contact strip 49, the path for the current through the conductors 18 and 38 being cut off.

20 The speed permitted under danger conditions is sufficiently slow to enable a quick stop to be made, but the train can proceed, should the apparatus be out of commission or other contingency exist, for otherwise 25 the train might be locked against any advance movement with the brakes set.

Clearing device.

The speed control of the vehicle is terminated 30 when the vehicle passes the track element or device set for clear, and the clearing device includes a switch 52 to which the conductor 34 is connected, and the switch when moved in one direction will engage contacts 53 connected by separate conductors 35 54 with the magnets 30 and 31 between said magnets and the respective switches 28 and 29.

The clearing switch 52 shunts the switches 40 28 and 29, so that the magnets 30 and 31 can be energized, providing the switch segments 32 and 35 engage the respective contacts 25 and 26.

Thus, with the switch 52 closed, the clearing 45 circuit of the magnet 30 includes the generator 14, conductor 27, disk 24, segment 32, contact 25, conductor 33, magnet 30, corresponding conductor 54 and contact 53, switch 52, and conductor 34, but if the switch segment 32 is removed from the contact 25, the magnet 30 will not be reenergized.

The clearing circuit of the magnet 31 includes the generator 14, conductor 27, disk 24, segment 35, contact 26, conductor 36, 55 magnet 31, corresponding conductor 54 and contact 53, switch 52, and conductor 34, requiring the segment 35 to be in engagement with the contact 26.

The switch 52 is closed before either segment 60 32 or 35 leaves its contact 25 or 26, respectively, when the disk 24 is turned in one direction, by a lug 55 which turns with said disk, but the lug in engaging the switch 52 during the turning movement of the disk in the opposite direction, will not close said

switch, the switch 52 being capable of swinging in opposite directions from a normal neutral position in which it is held by a spring or other equivalent means.

Responsive device.

The responsive trip device 23 is operated from the track element or device, and the disk 24 is mounted on a shaft 58 from which a trip member or arm 56 depends, and said pendant arm 56 is capable of swinging forwardly and rearwardly about the transverse axis of the shaft 58. The lower end of the member or arm 56 has a T-head 59 to contact with the tripper or tripping member of the track device.

The disk of the responsive device is housed within a casing 60 at one side of a partition 61 in said casing through which the shaft 58 is journaled. Said casing is secured to or suspended from the locomotive or vehicle in any suitable manner.

The contacts 25 and 26 are mounted in the casing 60, the contact 26 only being shown in Fig. 7, but the mounting of both contacts 90 being the same. As shown, the contact 26 is slidably mounted in a guide 62 of insulating material, and the contact is flanged to limit the inward movement thereof when the segment 35 is removed from the contact so that the segment can return into proper engagement with the contact. A coiled spring 63 is confined between the contact and a binding post 64 secured through a plug 65 of insulating material which is screwed into the casing 60 to retain the guide 62 in place. The wire or conductor 36 is connected to the binding post 64 in electrical connection with the contact 26, and the disk 24 can be grounded for connection with the conductor 27 leading to the generator, as seen in Fig. 1.

In order to yieldingly move the disk 24 and trip arm 56 to normal intermediate or neutral position, the collar 66 is secured on the shaft 58 at that side of the partition 61 opposite to the disk 24, and has oppositely extending arms 67 with which coiled springs 68 are connected, and said springs are anchored to adjusting screws 69 for regulating the tension of the springs. The screws 69 are mounted in extensions 70 of the casing 60. Such springs in contracting will turn the shaft 58 to intermediate position, and said shaft can turn in either direction.

The shaft 58 and arm 56 are hollow or tubular, and said shaft has an opening 71 for admitting air from a branch 72 of the brake pipe or train line which is connected to the casing 60, whereby should the arm 56 be broken off, the air can escape from the brake pipe to apply the brakes.

The lug 55 is carried by the collar 66, and the clearing switch 52 is mounted in the casing 60 in any suitable manner.

The controlling switch of the responsive

device is operable in one direction only for breaking the circuits, that is, when the arm 56 is swung toward the left, as seen in Figs. 1 and 7, the segments 32 and 35 being sufficiently long so as to remain in engagement with the contacts 25 and 26 when the arm 56 is swung in the opposite direction. The arrangement is such that when the arm 56 is swung in the operative direction a given distance, the lug 55 trips and closes the clearing switch 52; and when the arm 56 is swung through a larger angle, the segment 32 is removed from the contact 25 to open the circuit of the magnet 30; whereas if the arm 56 is swung still further the segment 35 is removed from the contact 26, thereby breaking the circuit of the magnet 31.

Track device.

20 The track device for controlling the responsive vehicle-carried device constitutes tripping means for tripping the arm or member 56 of the vehicle device, and for swinging said arm through different angles 25 for obtaining different controlling conditions accordingly.

30 The track device includes a tripper or tripping member 73 slidable through the top of a casing 74 which fits the outer side of a rail of the track, and said casing is fastened by bolts 75 or otherwise to the rail, thereby associating the track device directly with the rail. The tripper 73 is adapted to be projected upwardly into the path of the arm 35 56 for tripping said arm an amount corresponding to the height to which the tripper is raised, and said tripper is raised by the weight of the locomotive or vehicle so as to assure of positive action, without interference.

45 The actuating means for the tripper 73 includes a plunger 76 slidable through the top of the casing 74 in advance of the tripper 73, and the lower end or stem of the plunger 76 is slidable in a guide 77 secured to the bottom of the casing. A lever 78 has one arm pivotally connected with the plunger 76, and said lever is fulcrumed within the casing. Thus, the lever 78 is mounted on a shaft 79 which is journaled in the back of the casing 74 and a bearing 80 secured in the casing in front of the lever. A link 81 has its upper end pivotally connected, as at 82, to the other arm of the lever 78, and said link extends through an opening 83 in the bottom of the casing 73, and has its lower end pivotally connected with a lever 84 between the ends of said lever 84. The lever 84 is housed within a sub-casing 85 secured to the bottom of the casing 74 and arranged to go between two of the ties. The lever 84 is fulcrumed, at one end, as at 86, to one wall of the sub-casing 85. There is an operative connection between the lever 84 and tripper 73 providing for the lifting of the

tripper to different heights, according to track conditions, although the lever 84 is operated the same amount each time that the plunger 76 is depressed.

5 The tripper 73 has a stem 87 extending downwardly therefrom and slidable through an upstanding guide 88 secured to the bottom casing 73, and said stem has a plate 89 at its lower end disposed between a pair of plates 90 and 91 which have outstanding studs 92 at their opposite sides engaged by the forked end 93 of the lever 84, whereby the plates 90 and 91 are slid vertically when the lever 84 is oscillated. The plate 89 is disposed slidably between the plates 90 and 91, and pins 94 extend through the plate 89 and work in vertical slots 95 provided in the plates 90 and 91, whereby when the lever 84 is moved downwardly, the plates 90 and 91 striking the pins 94 at the upper ends of the slots 95 will depress the tripper 73.

20 In order to raise the tripper 73 to different positions, a pair of dogs 96 and 97 is provided, and said dogs are seated for swinging movement in recesses 98 in the plate 91, 25 whereby said dogs, when released, will fall by gravity against the plate 89 which has a notch or shoulder 99 to be engaged by said dogs. The dog 97 is of shorter length than the dog 96, to provide for a lost motion between the plates 89 and 90-91. Thus, when the dog 96 drops into the notch 99, the plate 89 and tripper 73 are raised to the maximum height when the plates 90 and 91 are raised, whereas when the dog 96 is held retracted 30 and the dog 97 drops into the notch 99, the plates 90-91 will raise a short distance before the plate 89 is raised by the dog 97, and the tripper 73 is therefore raised to a less height. If both dogs 96 and 97 are held retracted from the plate 89, the tripper 73 is raised to a still less height by the contact of the plates 90 and 91 with the pins 94 at the lower ends of the slots 95, said slots being of such a length as to provide for still greater lost motion between the plates 89 and 90-91 than when the plate 89 is raised by the dog 97. The lowest raised position of the tripper 73 provides for clearing or speed control terminating conditions, as indicated in Fig. 2, and the second raised position provides for caution conditions, while the third or highest raised position of the tripper provides for danger conditions.

40 The dogs 96 and 97 are under the control of the wayside signal apparatus (not shown), and, for this purpose, armatures 100 are pivotally connected to the upper end of the plate 91 and are suspended to swing by gravity toward the plate 89 to assist in moving the dogs into engagement with the plate 89. The armatures 100 are connected by links 101 with the dogs, and the armatures 100 are under control of the respective electromagnets 102 and 103 mounted in the sub-

casing 85. The magnet 102 is in a circuit of the wayside signal apparatus, whereby when the semaphore (not shown) is in caution position, the circuit of the magnet 102 is opened, to release the dog 97 so that it swings into the notch 99. The magnet 103 is in a circuit of the wayside signal apparatus whereby when the semaphore is at danger, the circuit of the magnet 103 is opened to release the dog 96. Should either magnet become deenergized by the accidental breaking or shortening of its circuit, the corresponding dog will be released, so that the track device is on the normal safety principle.

In order to prevent the tripper 73 from being thrown upwardly higher than intended, a ball or other detent 104 is slideable in the casing 85 and is pressed by a spring 105 against the plate 89, and said plate has notches 106 for the engagement of said ball in the different raised positions of the plate 89 and tripper. The ball 104 does not interfere with the intended motion of the tripper, but, in snapping into the notches 106 will prevent the tripper from being thrown upwardly further than intended.

The plunger 76 is depressed when the locomotive or vehicle passes the track device, so as to raise the tripper 73. This is accomplished by a wheel 107 of the locomotive or vehicle which has its tread or rim extended, as at 108, either by attaching an extension to the wheel or by providing it with an extra wide rim. The tripper 73 and plunger 76 are spaced sufficiently far from the rail so that the ordinary wheels do not pass over said tripper and plunger, but the extension 108 of the wheel 107 passes over the tripper and plunger, and depresses the plunger, thereby compelling the track device to operate under the weight of the locomotive or vehicle. The pressure on the plunger 76 is therefore sufficiently great to compel the track device to operate, and the working parts of the track device are sufficiently rugged and substantial so as to operate without failure. The plunger 76 can also be depressed by a shoe which rides on the rail, in the same manner that the plunger is depressed by the wheel 107, and said wheel 107 can be taken to represent a shoe of circular or other form.

Therefore, whenever the wheel or shoe 107 passes the track device, it will positively depress the plunger 76 for raising the tripper 73, and the responsive device of the vehicle is located sufficiently far behind the wheel 107 so that the tripper 73 is raised in front of the arm 56.

After the responsive device has passed the tripper 73, the tripper is retracted and the plunger 76 raised. This is accomplished, as shown, by a restoring plunger 109 which is slideable through the top of the casing 74

adjacent to the rail, and the plunger 109 is engaged with the pivot 82 between the lever 78 and link 81, whereby the setting plunger 76 and restoring plunger 109 move in opposite directions. Thus, when the setting plunger 76 is depressed, the plunger 109 is raised, and the plunger 109 is in the path of the ordinary wheels, so that the wheel which follows in rear of the responsive device will pass over and depress the plunger 109, thereby depressing the lever 84 and retracting the tripper 73, as well as raising the plunger 76.

Packing 110 is disposed in the top of the casing 74 around the plungers and tripper, to exclude water, moisture and other foreign matter from the casing. The casing has a partition 111 between the lever 78 and tripper 73, and the bottom of the casing 74 has drain apertures 112 for each chamber, in order that any water or moisture in the casing can drain out. The guide 88 prevents any water in the casing 74 from draining down along the stem 87 into the sub-casing 85, and the tripper 73 has an apron 113 depending therefrom and slideable on the guide 88 to exclude water and moisture from the casing 85. The bottom of the casing 74 has a raised portion 114 surrounding the opening 83, to prevent water from draining down through the opening 83. The casings 74 and 85 have the removable walls 115 and 116, respectively, for obtaining access to the interior parts.

Operation.

Clear conditions.—With the train proceeding under clear conditions between or beyond the control stations, the normal running circuit is closed so as to keep the magnet 15 energized, such circuit including the generator 14, magnet 15, brush 16, conductor 18, switch 20, conductor 21, switch 22, and conductor 27. The magnet 30 is kept energized to hold the switches 28 and 20 closed, by being included in the circuit including the generator 14, conductor 27, disk 24, segment 32, contact 25, conductor 33, magnet 30, switch 28 and conductor 34. The magnet 31 is kept energized to hold the switches 29 and 22 closed, by being in the circuit including the generator 14, conductor 27, disk 24, segment 35, contact 26, conductor 36, magnet 31, switch 29 and conductor 34.

Under clear track conditions, the magnets 102 and 103 are both energized so as to hold the dogs 96 and 97 retracted from the plate 89.

Now, when passing the control station, with the tripper 73 and plunger 109 down in retracted position, and the plunger 76 raised, the wheel 107 passes over the tripper and plungers, and the extension 108 of the wheel passing over the plunger 76 will depress

said plunger, so as to forcibly raise the plates 90-91. The plate 89 and tripper 73 are raised by the contact of the plates 90-91 with the pins 94, thereby raising the tripper the minimum amount to clearing or speed control terminating position. The arm 56 strikes the tripper 73 and is swung through a small angle in passing over the tripper, and the disk 24 is not turned sufficiently to remove either segment from its contact, but the movement is sufficient to enable the lug 55 to trip and close the clearing switch 52 for an instant, which will terminate the speed control, if it exists, as will hereinafter more fully appear. Then, when the arm 56 has passed the tripper 73, one of the wheels following in rear of the arm in passing over the plunger 109, will depress said plunger, thereby retracting the tripper 73 and raising the plunger 76. The track device is thus automatically reset after being set by the wheel 107, and the tripper 73 and plunger 109 are normally retracted below the horizontal plane of the tread of the rail. The plunger 76 is the only part that projects upwardly above such plane, but it will not constitute an objectionable obstruction.

It is also to be noted that the track device being set by the depression of the plunger 76 under the weight of the locomotive or vehicle, will cause the tripper 73 to be raised or projected with great force, so that it will break through ice, snow or other matter that may have accumulated on the casing 74, and the operation of the tripping device will not be interfered with. Furthermore, the wheel 107, and other wheels of the train, will serve to clear the path of the trip arm 56, so that said arm will not be interfered with by ice, snow, or other obstacles.

Caution conditions.—Under caution track conditions, the magnet 103 is deenergized, and the magnet 102 remains energized, so that the dog 96 is retracted while the dog 97 drops into the notch 99 of the plate 89.

Then, when the vehicle passes the tripping device, so that the wheel 107 depresses the plunger 76, the plate 89 and tripper 73 are raised by the dog 97, so that the tripper is lifted to its second or caution position. In this position, the tripper is slightly higher up than when in clearing position. Consequently, when the arm 56 passes over the tripper 73, said arm is swung through a sufficiently large angle to remove the segment 32 from the contact 25, and the tripper 73 and plunger 76 are then restored by the depression of the plunger 109 by one of the wheels following in rear of the arm 56.

The arm 56, after passing the tripper, is returned to normal intermediate position, by the springs 68, but the plunger 76 is not raised until the arm 56 has passed said

plunger 76. In other words, the arrangement is such that the plunger 109 is not depressed to raise the plunger 76 until the trip device on the vehicle has moved past the plunger 76, for otherwise the arm 56 might be tripped by the plunger 76, which would be objectionable, but this cannot happen with the arrangement as stated.

The removal of the segment 32 for an instant from the contact 25 will immediately deenergize the magnet 30, by opening the circuit of said magnet, to release the switch 28, so that the switches 20 and 28 are opened, thereby opening the normal running circuit at the switch 20 and establishing the caution speed control circuit. The switch 28 remains open so that the magnet 30 remains deenergized during caution conditions.

The caution speed control circuit includes the generator 14, magnet 15, brush 16, contact strip 37, conductor 38, conductor 21, switch 22 and conductor 27, the conductor 18 and switch 20 being shunted by the contact strip 37 and conductor 38. Should the train be moving above caution speed with the brush 16 above the contact strip 37, the magnet 15 will be deenergized to reduce the speed, and when the brush 16 engages the contact strip 37, the magnet 15 will be re-energized so that the train can proceed under caution speed but not above such speed. Should the speed allotted be exceeded, the brush 16 being removed from the strip 37 will immediately open the circuit of the magnet 15 and apply the brakes, thereby compelling obedience to the caution conditions.

Caution speed control is continued through the block, after passing the control station set for caution conditions, and when the magnet 30 has been deenergized, the switches 20 and 28 will remain open until the vehicle passes a tripping device set for clear conditions, as will hereinafter more fully appear.

Danger conditions.—When danger track conditions exist, the magnet 102 is deenergized, and the magnet 103 is also preferably deenergized.

Thus, when the train passes the control station, the depression of the plunger 76 by the wheel 107 will result in the plate 89 and tripper 73 being raised by the dog 96 which has dropped into the notch 99, and the tripper is therefore raised to its highest or danger position. The arm 56 will therefore be swung the maximum amount in passing over the tripper 73, thereby removing the segment 35 from the contact 26 as well as removing the segment 32 from the contact 25. This will immediately deenergize the magnet 31 by opening the circuit thereof, to release the switches 22 and 29, so that they drop open. Said switches remain open to continue the danger speed control until terminated by a clearing action.

The danger speed control circuit is established by the opening of the circuit of the magnet 31, and such circuit includes the generator 14, magnet 15, brush 16, contact 40, conductor 41, magnet 44, conductor 45, switch 46, conductor 47 and conductor 27. Two requirements are therefore necessary. First, the train must be brought to a stop in order that the brush 16 will engage the contact 40, and, second, the engineer or motorman must close the switch 46, before the brakes will be released, after the switch 22 has been opened by the danger impulse or signal. It will be noted that the switch 22 is disposed in the normal running and caution speed circuits, requiring the completion of the circuit of the magnet 15, under danger conditions, through the switch 46 and conductor 47. When the train has been brought to a stop and the switch 46 is closed, said preliminary danger speed control circuit is closed, thereby energizing the magnet 15, to release the brakes, and the magnet 44 is also energized to raise the switch 43 against the contact 48, thereby changing the circuit connections to include the danger contact strip 49. As a result, the train can proceed under restricted danger speed, as long as the brush 16 remains on the strip 49, but when proceeding under danger conditions, the engineer or operator must keep the switch 46 closed, so as to assure that he is alert. If the permissible danger speed is exceeded, the brush 16 being removed from the strip 49 will deenergize the magnet 15 to apply the brakes, and the magnet 44 being deenergized will let the switch 43 drop, thereby disconnecting the strip 49 from the circuit so that the train must again be brought to a stop before it can proceed further, as before. The danger speed is thus enforced, with a penalty in stopping the train if the speed is exceeded.

45 *Speed control termination.*

When the train is proceeding under either caution or danger speed control and it passes a control station set for clear, the vehicle equipment is brought to clear condition, for terminating speed control, and the danger speed control is also terminated when the control station is set for caution, so that the vehicle equipment can step up from danger to caution speed control.

50 Thus, when the vehicle passes a tripping device set for clear, with the dogs 96 and 97 retracted, so that the tripper 73 is only raised the minimum amount, the arm 56 is swung to close the switch 52, without removing the segments 32 and 35 from their contacts. Now, if the segments remain in engagement with the contacts, then a clearing action will take place to reenergize the magnets 30 and 31 for reestablishing clear conditions. The

switch 52 being closed will establish a clearing circuit including the generator 14, conductor 27, disk 24, segment 32, contact 25, conductor 33, magnet 30, corresponding conductor 54 and contact 53, switch 52, and conductor 34, so that the magnet 30 is energized to raise the switch 28 and restore the caution relay to normal position. However, the segment 32 must remain in engagement with the contact 25, and if the arm 56 is swung to caution or danger position, then the clearing circuit is broken at the same time that the normal circuit of the magnet 30 is broken, preventing the reenergization of said magnet. Consequently the magnet 30 must be deenergized under caution conditions, or if caution or danger conditions exist in the track equipment, said magnet 30 cannot be reenergized. Another clearing circuit includes the generator 14, conductor 27, disk 24, segment 35, contact 26, conductor 36, magnet 31, corresponding conductor 54 and contact 53, switch 52 and conductor 34, to reenergize the magnet 31, and raise the switches 22 and 29. However, the segment 35 must remain in engagement with the contact 26, and if the arm 56 is tripped to danger position, the segment 35 being removed from the contact 26 will prevent the magnet 31 from being reenergized.

Accordingly, if the arm 56 is tripped by the tripper 73 with the tripper in clear position, the clearing circuits of the magnets 30 and 31 are closed, so as to restore clear conditions in the vehicle equipment. Should the tripper 73 be in caution position, although the switch 52 is closed, the segment 32 is removed from the contact 25, thereby breaking the circuit of the magnet 30 so that said magnet will remain deenergized after passing the control station. However, if the train is proceeding under danger speed control when passing the track device, with the track device set for caution, so that the segment 32 is removed from the contact 25, whereas the segment 35 remains in engagement with the contact 26, the circuit of the magnet 30 is broken, but the clearing circuit of the magnet 31 is completed by way of the switch 52 and segment 35. The magnet 31 will therefore be reenergized to terminate danger speed control, but the magnet 30 being deenergized will enforce caution speed control. The switches 20 and 28 are therefore raised, so that the train can proceed under caution speed control. This enables the speed of the train to be increased from danger speed to caution speed, to avoid unnecessary retarded speed in a caution block after travelling in a danger block.

110 *Reverse travel responsive devices.*

115 Fig. 9 illustrates a pair of trip devices to be disposed at opposite sides of the locomo-

tive or vehicle, to take care of the travel of the vehicle in either direction, either for the purpose of enabling the vehicle to travel with either end forward, or to make provision for single track traffic in opposite directions, in which event the track devices are disposed at opposite sides of the track in reversed positions, as will be apparent.

The disks 24 and 24' of the two responsive trip devices turn with the pendant trip arms 56 and 56', respectively, and the disk 24 has the segments 32 and 35 while the disk 24' has the segments 32' and 35'. Said segments are insulated from the disks, and the contacts 25, 26, 25' and 26' engage the respective segments 32, 35, 32' and 35'. The segments of the two devices are in reversed positions, whereby the circuits are only broken by the segments 32 and 35 when the arm 56 is swung in the direction of the arrow, and the circuits are only broken by the segments 32' and 35' when the arm 56' is swung in the direction of the arrow. Said arms 56 and 56' must therefore swing in opposite directions to break the circuits, and when the arms are swung in the other directions, the circuits are not broken.

In using the two responsive devices, the conductor 33 leading from the magnet 30 is connected to the contact 25' and the conductor 36 leading from the magnet 31 is connected to the contact 26'. The segments 32 and 32' are connected by a conductor 33', and the segments 35 and 35' are connected by a conductor 36'. The contacts 25 and 26 are connected to the conductor 27 leading to the generator, so that the caution and danger segments are connected in series respectively. Each device has a clearing switch 52 operated by the movement of the corresponding arm in the proper direction, it being understood that the two responsive devices are in reversed positions, so that one is operative when the vehicle moves in one direction and the other responsive device is operative when the vehicle moves in the opposite direction.

Supposing the vehicle to be moving toward the right, as seen in Fig. 9, then the lower trip device would be operative, and should the arm 56' be swung toward the left, the circuits would not be broken at the contacts 25' and 26'. However, should the arm 56 be swung toward the left, clear, caution and danger conditions can be established according to the amount of movement of the arm, as hereinbefore explained. If the segment 32 is removed from the contact 25, then caution conditions are established in the same manner as hereinbefore described, and if the segment 35 is removed from the contact 26 then danger conditions are established.

Now, assuming that the vehicle is turned

around end for end, then the arm 56' would be the one to be operated in the same direction of travel on the track, but the reversal of the vehicle will bring the arm 56' into proper position for operation by the track devices, in the same manner that the arm 56 is operated as above described. In this case, with the vehicle travelling with its other end forward, the arm 56' would be swung by the trippers of the track devices for removing the segment 32' from the contact 25' and for removing the segment 35' from the contact 26' for caution and danger conditions, respectively.

The two responsive devices also take care of traffic in opposite directions on a single track, wherein the track is provided with tripping devices at opposite sides. Thus, the arm 56, when travelling toward the right, as seen in Fig. 9, would operate the segments 32 and 35 for establishing caution or danger conditions according to the track devices, and the swinging of the arm 56' would have no effect. However, if the vehicle is travelling in the opposite direction, then the swinging of the arm 56' toward the right, with the train travelling toward the left, will result in the segments 32' and 35' being removed from their contacts by the track devices, for establishing caution or danger conditions, and the movement of the arm 56 toward the right would have no effect.

Travel in reverse or opposite directions is thus taken care of by the two responsive devices, without using a reversing controller or switch, and without requiring the manual or automatic setting of a device for the purpose of taking care of travel in reverse directions.

Modifications.

Figs. 10 and 11 illustrate a modified form of tripping device, in which the resetting plunger 109 is eliminated, by disposing the tripper 73' closely adjacent to the rail, and the arm 56' is also arranged more nearly over the rail. This simplifies the track device and also enables the arm 56' to be more nearly over the rail so as to be better protected from interference. With this arrangement, the tripper 73' is raised in front of the arm 56' by the depression of the plunger 76', for swinging the arm 56' an amount according to the height to which the tripper is raised, and after the arm 56' has passed the tripper 73', a wheel following in rear will pass over the tripper 73' and depress same, thereby restoring the track device and raising the plunger 76'. With this arrangement, the plunger 76' is also out of the path of the arm 56', so that the plunger 76' can be raised before the arm 56' passes said plunger.

As seen in Fig. 11, the tripper 73' and

corresponding parts are disposed closer to the rail than in the first-described form of track device. A further modification is shown in said Fig. 11, wherein the armatures 100' are shown as integral with the dogs 96'. One dog drops into a notch 99' for raising the tripper the maximum amount for danger conditions, and the other dog drops into a longer notch 99'' to provide for lost motion so that the tripper is raised to caution position, so that the dogs can be of the same length.

Fig. 12 illustrates diagrammatically a pneumatic trip device that can be used on the vehicle in lieu of an electrical trip device. Such pneumatic device comprises a valve 24" mounted to turn in a casing 35", and said valve turns with the trip arm 56". Pipes 33" and 36" are connected to the casing, and the pipe 33" leads from a suitable pneumatic device to establish caution conditions when the air escapes from said device while the pipe 36" leads from a suitable pneumatic device for establishing danger conditions when the air escapes from said device. The casing 35" has an air discharge port 27" and the valve 24" has a passage 32" which communicates with said port 27". A lug 55" movable with the valve 24" is arranged to trip a lever 52" in one direction of movement of the valve 24" and arm 56" so as to operate a valve 53" for terminating caution speed control if the passage 32" is not moved into registration with either the pipe 33" or the pipe 36". If the arm 56" and valve 24" are moved further, the passage 32" is brought into registration with the pipe 33", thereby letting the air escape from said pipe to establish caution conditions, and if the valve is moved still further, the passage 32" is brought into registration with the pipe 36" thereby letting the air escape from the pipe to establish danger conditions.

Advantages.

The advantages and salient features of the present apparatus are as follows:

1. No track or wayside current is required for operating the track device or energizing the responsive device, thus providing for economy.
2. There are no clearance problems involved, the control elements or devices being associated with the rail.
3. There are no objectionable obstructions on the track or vehicle.
4. There are no isolated rail sections or insulated joints.
5. There are no induction problems or delicate sensitive responsive devices subject to interference by magnetic objects on the track, stray currents, etc.
6. There can be no interference with the operation by ice, snow, sleet, rain or the like.

7. The apparatus has the adaptability for various conditions and requirements and has flexibility for different methods of installation.

8. The control devices or elements are associated with the rail, affording protection against damage or false operations, and providing predetermined clearances.

9. Normal closed circuit control of the track device is provided resulting in caution or danger conditions if the track circuit are broken intentionally or accidentally.

10. A reliable mechanical contact trip device is provided.

11. One tripping device or element for different conditions, providing for simplicity.

12. Rugged construction of tripping device on the track to be operated positively and effectively by the weight of the locomotive or car for reliable operation of the responsive device.

13. There is no possibility of the track device sticking, catching or failing to operate as intended.

14. Travel in opposite directions is taken care of by responsive and control devices at opposite sides of the track, without using a reversing controller or switch.

15. An alert device is provided requiring the engineer to be alert when proceeding under danger conditions, so that he may manually bring the train to a stop quickly if necessary, whereas if he is not alert or performing his duty a compulsory stop will be made.

16. The speed control features are simple and desirable.

Having thus described the invention, what is claimed as new is:

1. Vehicle controlling apparatus comprising the combination with the rails of a track, and a vehicle having wheels travelling on said rails, with one wheel provided with an extended rim, of a tripper mounted on the track, a trip member carried by the vehicle to be tripped by said tripper in one position of said tripper, and actuating means operably connected with the tripper and arranged to be operated by said extended rim for moving the tripper to said position, and located out of the path of the other wheels.

2. Vehicle controlling apparatus comprising in combination with the rails of a track and a vehicle having wheels travelling on said rails, with one wheel provided with an extended rim, of a plunger mounted on the track arranged to be actuated only by said extended rim, a tripper operably connected with said plunger to be moved to tripping position thereby, and mechanism carried by the vehicle including a trip member to be tripped by said tripper.

3. A tripping device including a tripper

for tripping a vehicle carried member, actuating means, and controlled means for connecting the actuating means and tripper for moving the tripper to different positions by the operation of the actuating means.

4. A tripping device including a tripper for tripping a vehicle carried member, vehicle actuated means, and controlled means for connecting the vehicle actuated means and tripper to position the tripper at different positions when actuated by said vehicle actuated means.

5. A tripping device including a tripper, actuating means, and controlled means for connecting the tripper with the actuating means for the movement of the tripper to different positions by the operation of said actuating means.

6. A tripping device including a tripper for tripping a vehicle carried member, actuating means, and a plurality of controlled members for connecting the tripper with said means for the movement of the tripper to different positions by the operation of said means.

7. A tripping device comprising a tripper for tripping a vehicle carried member, actuating means, a plurality of dogs for connecting the tripper with said means to move the tripper to different positions, and independent controlling means for said dogs.

8. A tripping device comprising a tripper for tripping a vehicle carried member, actuating means, a plurality of dogs operable, when released, for connecting the tripper and actuating means for the movement of the tripper to different positions, and electro-magnetic means controlling said dogs when said electro-magnetic means are energized to disconnect said tripper and actuating means.

9. A tripping device comprising a tripper for tripping a vehicle carried member, actuating means operably connected with the tripper for moving the tripper to a predetermined position, and controlled means between said tripper and actuating means operable for moving said tripper to another position when said actuating means is operated.

10. A tripping device comprising a tripper, actuating means having an operative connection with the tripper for moving the tripper a minimum amount with some lost motion, and controlled means for connecting the tripper with said means for the movement of the tripper by said means with less lost motion, to move the tripper further.

11. A tripping device comprising a tripper, actuating means operatively connected with the tripper for moving the tripper a minimum amount, a dog to connect the tripper and said means for moving the tripper a further distance when the dog is in operative position, and means controlling said dog for moving it to inoperative position.

12. Vehicle controlling apparatus embodying a tripper on the track movable to different positions, a trip member carried by the vehicle and movable to different positions when tripped by said tripper, means for establishing a vehicle retarding condition when said member is moved a predetermined amount, and means for eliminating such condition when said member is moved less than such amount.

13. Vehicle controlling apparatus embodying a tripper on the track movable to different positions, a vehicle carried trip member arranged to be tripped to different positions by the tripper, means for establishing a caution condition when said member is moved a predetermined amount, means for establishing a danger condition when said member is moved a further amount, and means for eliminating either or both of said conditions when said member is moved a less amount than that first stated.

14. Vehicle controlling apparatus embodying a tripper on the track movable to different positions, a vehicle carried trip member adapted to be tripped to different positions by the tripper, an electrical control device, means for breaking the circuit of said device when said member is moved a predetermined amount, and means for reestablishing the circuit of said device when said member is moved a less amount.

15. Vehicle controlling apparatus embodying a tripper on the track movable to different positions, a vehicle carried trip member adapted to be tripped to different positions by the tripper, an electrical caution device, an electrical danger device, means for breaking the circuit of the caution device when the trip member is moved a predetermined amount, and means for breaking the circuit of the danger device when the trip member is moved a further amount.

16. Vehicle controlling apparatus embodying a tripper on the track movable to different positions, a vehicle carried trip member adapted to be tripped to different positions by the tripper, an electrical caution device, an electrical danger device, means for breaking the circuit of the caution device when the trip member is moved a predetermined amount, means for breaking the circuit of the danger device when the trip member is moved a further amount, and means for reestablishing the circuits of said devices when said member is moved a less distance than that first stated.

17. In a vehicle controlling apparatus, a pair of responsive trip devices to be carried by a vehicle, and electrical switches operated by said devices for controlling electrical vehicle controlling means, one device being operable in one direction longitudinally of the track and the opposite device being oper-

able in the other direction, the switches of the two devices being reversed.

18. Vehicle controlling apparatus embodying the combination with the rails of a track and a vehicle having wheels travelling on the track, of an extended rim on one of said wheels, and controlling means having an

actuating member mounted on the track and arranged to be operated only by said extended rim.

In testimony whereof I hereunto affix my signature.

ALFRED L. RUTHVEN.
